CLAIM

The ornamental design for a display for electronic book, as shown and described.

DESCRIPTION

FIG. 1 is a perspective view of a display for electronic book showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of another embodiment of a display for electronic book, shown with unclaimed portions in an open position;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof; and

FIG. 15 is a perspective view thereof, shown with unclaimed portions in a closed position;

FIG. 16 is a perspective view of still another embodiment of a display for electronic book, showing our new design;

FIG. 17 is a front elevational view thereof;

FIG. 18 is a rear elevational view thereof;

FIG. 19 is a left side elevational view thereof;

FIG. 20 is a right side elevational view thereof;

FIG. 21 is a top plan view thereof; and,

FIG. 22 is a bottom plan view thereof.

The broken lines shown in the drawings are for the purpose of illustrating unclaimed portions of the display for electronic book and form no part of the claimed design.
